SHARPENING DEVICE

Albert P. Komow, New York, N. Y.

Application April 5, 1938, Serial No. 200,080

7 Claims. (Cl. 51—249)

My invention relates to a new and improved sharpening device for cloth cutting machines.

One of the objects of the invention is to provide a sharpening device for a cloth cutting machine of the straight-knife type, in which a straight knife is caused to reciprocate, usually in a vertical direction.

Another object of the invention is to provide an attachment for this purpose, which can be affixed to a cloth cutting machine, preferably permanently, whereby, upon actuating a suitable control member, the sharpening device will automatically turn and also move vertically from an upper initial or inoperative position to a lower operative position in which the grinders will contact with the knife, and said sharpening device will then be moved vertically to sharpen the knife. Said sharpening device will then automatically turn back to its original inoperative and normal position.

Numerous other objects of the invention will be stated in the following description and drawings which illustrate a preferred embodiment thereof, it being understood that the above statement of the objects of my invention is intended generally to explain the same without limiting it in any manner.

Fig. 1 is a front elevation showing the sharpening device a little below the top position thereof, and with the sharpening devices or grinding wheels contacting with the edge of the knife. Said position of the grinding wheels is also illustrated in Fig. 9. The sharpening attachment is moved upwardly from the position illustrated in Fig. 1, to its top position, while it is turned from the angular position shown in Fig. 9 to the angular position shown in Fig. 10.

Fig. 2 is a side elevation of the device shown in Fig. 1. The full-line positions of the sharpening members and other parts indicate the positions which correspond to the position of said parts shown in Fig. 1, and the broken-line positions of said sharpening members and of the other parts indicate their bottom positions.

Fig. 3 is a front elevation, similar to Fig. 1, but showing the sharpening members at the bottom end of the knife.

Fig. 4 is a perspective diagrammatic view of the sharpening attachment when it has been moved upwardly to its highest position.

Fig. 5 is a diagrammatic perspective view showing, in addition to other parts, the presser-foot of the cutting machine, and showing the presser-foot when it has been moved to its upper position.

Fig. 6 and Fig. 7 are respectively sectional views on the lines 6—6 and 7—7 of Fig. 3.

Fig. 8 is a sectional view on the line 8—8 of Fig. 7.

Fig. 9 is a sectional view on the line 9—9 of Fig. 3, showing the grinders contacting with the knife.

Fig. 10 is a view similar to Fig. 9, showing the sharpening device after it has been turned around a vertical axis, away from the position shown in Fig. 9. This corresponds to Fig. 4.

Fig. 11 is a view similar to Fig. 10, and showing how the control device is moved manually in order to start the actuation of the sharpening device.

Referring to Fig. 1, the cloth cutting machine can be of any conventional construction. It has a base 1 and a standard 2, in which a knife 3 is mounted, so that the knife can reciprocate. The mechanism for vertically reciprocating the knife 3 is not shown, as in itself it is old and well known. The motor for actuating the knife 3 is located in the usual casing 4, and the machine has the usual hand-hold 5. The presser-foot rod 6 is of the usual type, and it is mounted slidingly in a slot which is provided in a guide 7, which projects from the casing 4. A clamping screw 8 is movable in a collar 9, which is mounted slidably upon the rod 6.

The point of screw 8 can be clamped against rod 6. When the collar 9 abuts the top wall of guide 7, the further descent of rod 6 is stopped.

The presser-foot 10 is suitably connected to the bottom of the rod 6.

The sharpening device or attachment comprises a pair of grinders 11 and 12, as shown in Fig. 4. These grinders 11 and 12 are mounted upon shafts 14 and 15. The shaft 14 is provided with a worm gear 16. The shaft 15 is provided with a worm gear 17. These gears 16 and 17 mesh with oppositely threaded worms 18 and 19, which are provided on a shaft 20. The shaft 20 is driven by a suitable auxiliary electric motor or by other means. This electric motor (not shown) is located within a casing 21. The electric motor 40 for turning the shaft 20 may be but is preferably not the same motor which reciprocates the knife.

The shaft 14 is mounted in a bearing 22, part of which is connected to the housing 21 by screws 22d. The shaft 15 is mounted in a bearing 23, which is slidable upon the rod 24, which is connected to another part of the bearing 22. As shown in Fig. 6, bearing 22 consists of members 22a and 22b, connected by screws 22c. Member 22b may be integral with, or it may be connected

to housing 21. Bearing 23 consists of members 23a and 23b, connected by screws 23c.

As shown in Fig. 6, said bearings 22 and 23 have bushings which serve as bearings for shaft 20.

5 A compression spring 25, mounted upon rod 24, is located between the bearing members 22a and 23a. The member 23a is held in adjusted position upon the rod 24, by means of a nut 26. The outer end of the member 24 is externally threaded so as to cooperate with the nut 26. Spring 25 operates to push member 23a away from member 22a, until member 23a abuts the inner end of nut 26. The distance between 10 bearings 22 and 23 can thus be adjusted.

15 As shown in Fig. 4, the housing 21 is horizontally slideable relative to a top casting 27, whose bottom surface is provided with a dove-tail groove. The top of the housing 21 is provided 20 with a dove-tail lug which fits slidably in the groove of the casting 27. A clamping screw 28 holds the members 21 and 27 in suitable adjusted position. The housing 21 is also provided with a lug 29. A threaded rod 30 passes 25 slidably through the untapped bore of the lug 29. The rod 30 is rigidly secured to the boss 31 of the casting 27. A nut 32 is mounted upon the rod 30. A compression spring 33 is located between the lug 29 and the boss 31. This spring 30 urges the housing 21 to slide relative to casting 27, until lug 29 abuts nut 32.

20 By turning the nut 32, the housing 21 can be located in horizontal adjusted position relative to the casting 27. The clamping screw 28 35 is then turned to hold housing 21 in said adjusted position. Said casting 27 includes a sleeve 34 which is provided with a cam-sleeve extension 36. This extension 36 has a wall which is curved and inclined to the vertical central axis of said 40 extension 36.

25 A rod 35 is located within said cam-sleeve extension 36 and said rod 35 is connected to the cam-sleeve extension 36, so that rod 35 and extension 36 move vertically in unison, and they 45 also turn in unison. The rod 35 passes through a suitable hub 38 which is provided in a bracket arm 37. Said hub 38 has the rod 35 keyed thereto, so that the bracket arm 37 and the rod 35 turn in unison around the longitudinal axis of the hub 38. Rod 35 is slideable vertically in hub 50 38. The keyway or slot 39 of the rod 35 is shown in Figs. 2 and 4.

30 The bracket-arm 37 is turnably assembled by means of its hub 38 and rod 35 with a bracket 55 40 which is fixed to the frame of the machine by means of screws 41. Said bracket 40 has upper and lower bosses 42, which have bores which are aligned with the bore of the hub 38, so that the rod 35 extends through said bosses 42. A 50 torsion spring 43 has the lower end thereof connected to the wall of the hub 38, and the upper end of said spring 43 is connected to a bushing 44 which has a knurled head 45. The shank of the bushing 44 fits snugly in the bore of the 60 top boss 42. The head 45 of the bushing 44 can be held against turning relative to the upper boss 42 by means of a set-screw 46 or other suitable means. The torsion spring 43 urges the bracket-arm 37 and its associated parts to turn 65 70 so that the grinding wheels 11 and 12 are brought into the operative position shown in Fig. 9 relative to the edge of the cutting knife.

75 Since rod 35 cannot turn relative to hub 38, said rod 35 serves as a pivot pin.

75 The casing 21, together with the auxiliary

motor located therein, and the rod 35, are moved upwardly in unison by drive means actuated by the auxiliary motor. As shown in Fig. 4, the shaft 14 is provided with a worm 47, which meshes with the worm wheel 49, which is mounted on a shaft to which a sprocket 49' is connected. As shown for example in Fig. 1 and Fig. 4, an endless chain 50 meshes with said sprocket 49'. Said chain 50 also meshes with an idler sprocket 51, and with a sprocket 52 which is turnably connected by shaft 53 to the bracket-arm 37.

15 As previously stated, said bracket-arm 37 can be turned relative to the frame of the cloth-cutting machine, but it cannot be moved up or down relative to said frame.

As shown in Fig. 4, the shaft 53 of the sprocket 52 is provided with a disc 54 having four identical lugs 55 which are spaced apart by arcs of 90°. The angular spacing between lugs 55 can be varied, and the number of lugs can be varied. 20 Sprocket 52 and disc 54 turn in unison.

25 As shown in Fig. 1, the chain 50 depends from the sprockets 49' and 52, a box 56 being provided to receive the loose bottom part of said chain 50.

The idler 51 and the sprocket 49' are turnably mounted upon the same vertically movable bracket, said bracket being shown in Fig. 2.

Therefore, when the sprocket 49' is turned clockwise, referring to Fig. 4, and the sprocket 30 52 is held against turning, the casing 21 and its associated parts, such as the stones 11 and 12, will be raised.

35 The disc 54 is held against turning when one of its lugs 55 abuts a stop-arm 57 which is rigidly connected to the frame of the machine. The stop-arm 57 is provided with an extension 58 which is connected by means of a screw 59 to the frame of the machine.

40 When the casing 21 is raised to a predetermined height, the cam wall of the cam-sleeve extension 36 cooperates with a fixed pin 60 which is suitably fixed to the bracket 40. Since the pin 60 is held stationary while the casing 21 is moved upwardly, the cam-sleeve 36 is turned in 45 unison with the rod 35 and with the bracket-arm 37 and housing 21, so as to cause the lug 55 which then abuts stop-arm 57, to turn from the position shown in Fig. 9 to the position shown in Fig. 10.

50 In Fig. 4, the housing 21 is shown at the end of its upward movement. In this position the lug 55 which then abuts the stop-arm 57 does not clear said stop-arm 57. However, the switch-operating arm 61, which is fixed to the extension 55 62 of the bracket-arm 37, is then turned in unison with bracket-arm 37 from the position shown in Fig. 9 to the position shown in Fig. 10, which corresponds generally to Fig. 4. In the position 60 shown in Fig. 10 the arm 61 inwardly presses the head 63 of a rod 64, so as to separate the two terminals of the switch 65, and thus break the circuit of the auxiliary motor.

65 The conventional parts of this switch 65 need not be described in detail, and this switch is conventionally illustrated in Figs. 9-11. It is mounted on housing 21. When the switch is in the circuit opening position shown in Fig. 10 (for example), the sharpening device is in its 70 top or initial position.

75 While the parts are in the positions shown in Fig. 10, with the stop-arm 57 abutting one of the lugs 55, the operator can manually turn the bracket-arm 37 against the force of spring 43, by 75

pressing upon its extension 62, so that the respective lug 55 clears the stop-arm 57, as illustrated in Fig. 11. Torsion spring 43 normally maintains the sharpening members 11 and 12 in the position shown in Fig. 9, when pin 60 is spaced from the cam-wall of member 36.

The weight of the auxiliary motor then causes the vertically movable parts of the attachment to descend to the position shown in Fig. 3. Likewise the torsion spring 43 operates to turn the rod 35 and the bracket-arm 37 so that the grinding stones 11 and 12 abut the edge of the knife, as shown in Fig. 3 and Fig. 9.

While the knife is being sharpened, it is preferably maintained stationary.

The downward movement of the casing 21 may be quite rapid. As soon as the torsion spring 43 has turned the bracket-arm sufficiently away from the position shown in Fig. 10, the circuit of the auxiliary motor is closed, as shown in Fig. 9.

Therefore, the auxiliary motor can operate the grinding stones while the auxiliary motor is descending.

A dash-pot or like device (not shown) may be provided, so that the torsion spring 43 does not turn the parts too rapidly from the position shown in Fig. 10 to the position shown in Fig. 9, so that the grind stones 11 and 12 first contact with the knife at the bottom of the knife, as shown in Fig. 3 and in broken lines in Fig. 2.

As soon as the circuit of the auxiliary motor is closed, sprocket 49' is turned. However, the lugs 55 can not strike against stop-arm 57, until the device is turned counterclockwise, from the position shown in Fig. 11 to a position in which said arm 57 is located in the path of movement of lugs 55. This counterclockwise movement may be delayed manually, or by a dash-pot or the like, until casing 21 has completed its downward movement.

Hence switch 65 will not be closed until the casing 21 is in the bottom position shown in broken lines in Fig. 2. This is preferred. Arm 57 may be somewhat resilient.

The stop-screw 66 is provided for limiting the turning movement of the rod 35 and of the bracket-arm 37, when the sharpening members 11 and 12 are moved by spring 43 to the position shown in Fig. 9. This screw 66 passes through a tapped opening in a bearing extension of the bracket 40. The member 69 holds the screw 66 in its adjusted position. This conventional form of releasable detent is used throughout, whenever an adjusting screw is included in the apparatus.

As shown in Fig. 5, when the attachment is moved upwardly, member 23a abuts presser-foot 10, so as to raise rod 6 and the presser-foot 10.

As shown in Fig. 5, the guide or frame member 1 is provided with a lateral bore which is provided with a detent 70. A spring 71 urges the detent 70 to move so as to release said detent from the rack-teeth of the rod 6. An eccentric 72 is provided at the end of a shaft 73, which is provided with a hand-hold 14. The shaft 73 extends through a bearing 75 which is connected to the frame of the machine. A torsion spring 76 actuates the shaft 73 so that its eccentric 72 will hold the detent 70 in locking position, so as to hold the rod 6 against vertical movement. The shaft 73 is provided with a collar having a lug 77. An arm 78, having a cam-portion 78b, is connected at its end-portion 78a by means of a set-screw 79 to the bracket-arm 37.

Hence, when the bracket-arm 37 is turned, the cam-arm 78b operates to actuate the lug 77 so as to move the eccentric 72 to the position in which it permits the detent 70 to clear the rack-teeth of the rod 6, under the force of spring 76.

Therefore, when the bracket-arm 37 is turned to the position shown in Fig. 11 and the attachment is moved to its bottom position, and the attachment is then turned to the angular position shown in Fig. 9 and said attachment is then moved upwardly, the upward movement of the attachment from its bottom position raises the rod 6 together with the presser-foot 10. As the attachment is moved upwardly close to its top position, the stationary pin 60 engages the cam surface of the cam sleeve 36 so that the bracket-arm 37 is turned until the parts are turned to the position shown in Fig. 10, in which position the switch 65 of the auxiliary motor is held open.

Likewise, in this position, the cam-arm 78b clears the lug 77 so that the rod 6 is held locked in its upper position.

The shaft 73 is then turned by means of the hand-hold 14, thus permitting the rod 6 to drop until its collar 9 abuts the top of the member 7.

Referring to Fig. 10, the torsion spring 43 tends to move the parts into the position shown in Fig. 9, but this is prevented by the pin 60 which abuts the notched bottom end of the cam wall of member 36.

The attachment cannot drop from its top position because one of the lugs 55 abuts the member 57, as shown in Fig. 10.

The rod 35 is provided with a head 35b and a cushioning spring 35a abuts the head 35b when the attachment drops to its bottom position as illustrated in Fig. 3.

While the invention is particularly useful as an attachment to a cloth cutting machine, it can be applied for various purposes where it is desired to sharpen the knife, or where a sequence of automatic movements of the type described herein may be useful for polishing or otherwise operating upon a stationary member. When the sharpening attachment is in its initial top inoperative position, the angular position of the arm 37 is shown in Fig. 10. As shown in Fig. 3, the member 36 has a notched or recessed position, and the fixed pin 60 then engages said recessed portion. The sprocket 52 is then held against turning, because the disc 54 is on the shaft 53 of sprocket 52, and one of the lugs 55 of the disc 54 then abuts the stop-arm 57. The chain 50 then meshes with the sprocket 49', and this cannot turn because the circuit of the auxiliary motor in housing 21 is then open, as shown in Fig. 10. Since the sprocket 49' is connected to the shaft 20 of the auxiliary motor to various intermediate parts, said sprocket 49' will not move relative to the chain 50, as long as the circuit of the auxiliary motor is open.

When it is desired to grind the knife 3, said knife 3 is moved to the position shown in Figs. 1 and 2, and the circuit of the main motor in the casing 4 is then opened, so that the knife 3 is held stationary.

The operator then presses with one hand upon the extension 62 of the arm 37, so as to turn said arm 37 clockwise from the position shown in Fig. 10 to the position shown in Fig. 11. In said position the respective lug 55 clears the stop-arm 57, so that the sprocket 52 is free to turn. While one hand of the operator holds the arm 37 in the position shown in Fig. 11, the operator can use his other hand to push down-

wardly upon the casing 21, although this is not necessary. When the arm 37 is thus turned clockwise, the members 35 and 36 are turned in unison with said arm 37. The recessed portion of the member 36 therefore clears the fixed pin 60 so that the casing 21 is free to descend, in unison with the members 36 and 35.

When the operator releases the arm 37, after it has been turned to the angular position shown in Fig. 11, the torsion spring 43 operates to turn the arm 37, towards the position shown in Fig. 9. This counterclockwise turning movement of the arm 37 is controlled by the cam surface of the member 36 and the pin 60. Likewise, this counterclockwise turning movement of the arm 37 can be controlled by means of a dash-pot, if desired, as previously stated. Therefore in the preferred embodiment, the grinding stones 11 and 12 have been moved to their bottom position, before said stones 11 and 12 contact with the edge of the knife.

When the circuit of the auxiliary motor is closed, the sprocket 49' actuates the chain 50, so as to turn the sprocket 52. However, when the parts are in the angular position shown in Fig. 9, the stop-arm 57 is in the path of movement of the lugs 55. Therefore the sprocket 52 will be held stationary, and the turning movement of the sprocket 49' will operate to raise the attachment, to the position shown in Fig. 1. The fixed pin 60 then contacts with the top of the cam-surface of the member 36, so that the further upward movement of the attachment causes the arm 37 to turn from the position shown in Fig. 9 to the position shown in Fig. 10, thus opening the circuit of the auxiliary motor, and stopping the operation of the attachment.

For convenience, some of the claims include reference numerals but the inclusion of such reference numerals does not limit the invention to the details described herein as numerous changes and omissions can be made without departing from the spirit of the invention.

For convenience, the device is described and claimed with the knife in vertical position, but this can be varied without departing from the invention. The invention is not restricted to a machine having a straight knife.

The invention is also not limited to the use of grinders or the like which are actuated when the sharpening device is moved in a direction parallel to the edge of the knife.

In order to define the essential terms which are used in the claims, the sharpening device is the bracket-arm 37 and the parts which are connected thereto, save that members 11 and 12 are designated as sharpening means. The position of the sharpening device which is shown in Fig. 10 is its normal predetermined position. The shaft 20 constitutes motor-driven means to raise the sharpening device, and pin 60 and cam-sleeve extension comprise cooperating means which hold the device against turning against the force of spring 43.

The claims also cover certain valuable sub-combinations, as well as the complete combinations of the invention.

I claim:

1. In combination with a cutting machine having a frame and a movable knife mounted in said frame, a sharpening device, said sharpening device having sharpening means, said sharpening device being mounted in said frame so that said sharpening device is bodily movable to-and-fro relative to said frame in a direction substantially

parallel to the edge of said knife and said sharpening device is also turnable relative to said frame so that its sharpening means can contact with said edge, and said sharpening means can be spaced from said edge, said sharpening means being spaced from said edge when the sharpening device is in predetermined normal position relative to said knife, motor-driven means operable to bodily actuate said sharpening device in a direction substantially parallel to said edge, a control switch for said motor-driven means, said device having an arm operable to hold said switch open when said device is in said normal position, spring means operable to turn said sharpening device away from said normal position until its sharpening means contact with said edge, said device and said frame having cooperating means operable to hold said device against the turning force of said spring when said device is in said normal position.

2. A device according to claim 1 in which said motor-driven means are operative to actuate said sharpening device only in one direction.

3. In combination with a cutting machine having a frame and a reciprocating knife, a sharpening device having sharpening means, said sharpening device being mounted in said frame so that said sharpening means are bodily movable to-and-fro relative to said frame in a direction parallel to the edge of said knife and said sharpening device is also turnable relative to said frame so that said sharpening means can contact with said edge or said sharpening means are spaced from said edge when the sharpening device is in predetermined normal position relative to said edge, said device having a motor-driven shaft 20, a first sprocket 49' connected to the motor-driven shaft 20 and turned thereby, a second sprocket 52 turnably connected to said device, and endless chain 50 meshed with said second sprocket 52 and having one run thereof in mesh with said first sprocket 49', the shaft of second sprocket 52 having a stop-wheel 54 connected thereto, said stop wheel 54 having spaced lugs 55, a stop-arm 59 connected to the frame and mounted to project into the path of the turning movement of said lugs 55 when the device is in said normal position, a spring 43 operable to turn the device away from said normal position until the sharpening means of said device contact with the edge of the knife, said device and said frame having cooperating means 36 and 60 operable to hold the device in said normal position against the force of the spring 43, said motor-driven shaft 20 having a control-switch 65 connected to said device, said device having means operative to hold said switch 65 open when the device is in said normal position, said device being turnable until the lugs 55 clear the stop-arm 57, said device being then free to move parallel to the edge of the knife.

4. A device according to claim 3 having a presser-foot 10 connected to a rod 6 which is mounted movably in the frame, movable latch-means operable to hold said rod 6 against movement relative to the frame, said device having control means 78b operable to release said latch-means when the device is turned away from said normal position, a part of said device abutting and moving said presser-foot when the device is actuated by said motor-driven means.

5. A cloth cutting machine having a frame and a knife mounted to reciprocate vertically relative to said frame in a stroke which has a top end and a lower end, a sharpening device having

sharpening-means, said sharpening device being mounted on said frame so as to be bodily movable relative to the frame to-and-fro in a direction parallel to the edge of the knife and said 5 sharpening device being also turnable so that its sharpening-means either contact with the knife or are spaced therefrom, spring means operative to turn the sharpening device until its means contact with the knife, said device and said frame 10 having cooperating means operable to hold the device against the force of the spring in a predetermined normal position in which said sharpening means are spaced laterally from the knife and spaced vertically from the lower end of the 15 stroke of the knife, motor-driven means operative to raise the sharpening device while its sharpening-means are held in contact with the

knife, a control switch for said motor-driven means, said device having means to hold said switch open when the device is in said predetermined normal position.

6. A device according to claim 1 in which said 5 cooperating means are located and shaped to turn said device so that its sharpening means are moved away from said edge shortly before the completion of the movement of said device to the level of said normal position.

7. A device according to claim 3 in which said 10 cooperating means are located and shaped to turn said device so that its sharpening means are moved away from said knife shortly before the completion of the movement of said device 15 to the level of said normal position.

ALBERT P. KOMOW.
